(57) **CLAIM**

The ornamental design for a tire, as shown and described.

DESCRIPTION

FIG. 1 is a front elevation view of a tire showing my new design, it being understood that the pattern repeats uniformly throughout the circumference of the tread;

FIG. 2 is a enlarged partial elevation view thereof;

FIG. 3 is a front perspective view thereof;

FIG. 4 is a left side elevation view thereof; and,

FIG. 5 is a right side elevation view thereof.
